CLAIM

The ornamental design for a combined elbow and swivel with a rotatable pressure port, as shown and described.

DESCRIPTION

FIG. 1 is a top, front, and right side perspective view of a combined elbow and swivel with a rotatable pressure port embodying our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross sectional view taken along line 8-8 of FIG. 7.
